188,073

COMBINATION CARRYING AND STACKING CASE

Stanley P. Lovell, 65 Prospect Park, Newtonville, Mass.

Filed May 15, 1959, Ser. No. 55,932

Term of patent 14 years

(Cl. D58—5)

FIG. 1

FIG. 2

Fig. 1 is a view in perspective of a combination carrying and stacking case showing my new design, and

Fig. 2 is a plan view of the bottom of the case as seen from beneath.

The sides of the case not shown are the same as the sides shown in Fig. 1.

I claim:

The ornamental design for a combination carrying and stacking case, substantially as shown and described.
